US0D1072337S

(12) **United States Design Patent** (10) Patent No.: **US D1,072,337 S**
(45) Date of Patent: ** Apr. 22, 2025

(54) **ELECTRONIC CIGARETTE ATOMIZER**

(71) Applicant: **SHANDONG SINOCERA
FUNCTIONAL MATERIAL CO.,
LTD.**, Dongying (CN)

(72) Inventors: **Guanliang Sun**, Dongying (CN); **Bin Yang**, Dongying (CN); **Haitao Wu**, Dongying (CN); **Rongyan Sun**, Dongying (CN); **Yong Li**, Dongying (CN); **Hong Ying**, Dongying (CN); **Xiaolei Sui**, Dongying (CN); **Xiaolei Gao**, Dongying (CN); **Binbin Zhu**, Dongying (CN)

(73) Assignee: **SHANDONG SINOCERA
FUNCTIONAL MATERIAL CO.,
LTD.**, Dongying (CN)

(**) Term: **15 Years**

(21) Appl. No.: **29/914,828**

(22) Filed: **Oct. 23, 2023**

(30) **Foreign Application Priority Data**

May 5, 2023 (CN) 202330256059.7

(51) LOC (15) Cl. **27-07**

(52) U.S. Cl.

USPC **D27/162**

(57) **CLAIM**

The ornamental design for an electronic cigarette atomizer, as shown and described.

DESCRIPTION

FIG. 1 is a front perspective view of an electronic cigarette atomizer showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
